WOVEN ELASTIC FABRIC

John V. Moore, Pawtucket, R. I., assignor to Moore
Fabric Company, Pawtucket, R. I., a corpora-
tion of Rhode Island

Application March 3, 1938, Serial No. 193,752

2 Claims. (Cl. 139—421)

This invention relates to a woven elastic fabric or webbing in which the front and back of the fabric have distinctively different characteristics.

It is the general object of my invention to provide a woven elastic fabric having a relatively soft back and having a non-absorbent, hard-finish face adapted to receive a suitable dressing by which it may be caused to simulate leather.

It is a further object of my invention to provide 10 an elastic fabric having a face formed largely of non-absorbent hard-finish threads and having a back formed largely of threads having a soft surface, such as rubber threads with a soft and relatively thick cotton covering or soft non-elastic threads.

My invention further relates to arrangements and combinations of parts which will be hereinafter described and more particularly pointed out in the appended claims.

Preferred embodiments of my invention are shown in the drawings, in which

Fig. 1 is a plan view of a portion of a weave disclosing my invention;

Figs. 2, 3 and 4 are sectional views, taken along 25 the lines 2—2, 3—3 and 4—4 in Fig. 1 respectively;

Fig. 5 is a plan view of a portion of a different weave which also discloses my invention; and

Figs. 6 and 7 are sectional views, taken along the lines 6—6 and 7—7 in Fig. 5 respectively.

Referring to Figs. 1 to 4, I have shown face threads 10, backing threads 11, and additional threads 12 which act as binders. The threads 10 which float on the face of the fabric and largely constitutes said face, are preferably non-elastic and of relatively large size, and have a hard-finish, water-repellent or non-absorbent surface. Such a thread may be made of cotton or other fibre and may be glazed or coated with lacquer to provide an outer surface having said characteristics.

The threads 11 which largely constitute the back of the fabric are preferably formed with a rubber core and with a soft and relatively thick covering wound thereon. The additional threads 45 12 are non-elastic and are preferably of relatively small size, in comparison with the threads 10 and 11.

My improved fabric may be woven with the hard-finish threads 10 inserted as weft or filling and with the threads 11 and 12 used as warp, or the fabric may be woven by using the hard-finish threads 10 as warp and the threads 11 and 12 as weft or filling, in which latter case a double shuttle loom would be utilized.

In Figs. 5, 6 and 7 I have shown a second em-

bodiment of my invention in which the hard-finish face and soft back are both formed of non-elastic threads, all disposed in parallel relation in the fabric, while the rubber threads, together with additional non-elastic threads, extend at 5 right angles thereto and are interwoven therewith. The hard-finish, non-elastic threads 20 and soft, non-elastic threads 21 extend in one direction in the fabric and the covered rubber threads 22 and relatively small non-elastic threads 23 10 extend transversely with respect to the threads 20 and 21.

The various elements of the weave are so interwoven that the hard-finish threads 20 float on the face of the fabric and are held in place by 15 certain of the small non-elastic threads 23, which act as binders for the float threads. The soft, non-elastic threads 21 float similarly on the back of the fabric and are also retained by others of the small non-elastic threads or binders 23. 20

With this construction, the face of the fabric very largely comprises the hard-finish threads 20, while the back of the fabric is formed very largely from the soft threads 21. These two sets of threads 20 and 21 may differ not only in finish 25 but also in color and material, so that the inner and outer faces of the fabric may be strongly contrasted as to color and material as well as in respect to the hardness or softness of finish. The face of the fabric, composed very largely of the 30 hard-finish threads 20, may be dressed to simulate leather as in the construction previously described.

In this second weave also, the face threads 20 and back threads 21 may be either weft or warp, 35 and the rubber threads 22 and small non-elastic threads 23 may be either warp or weft. In either case, a double shuttle loom will be employed. In the more usual construction, the threads 20 and 21 will be weft or filling, while the threads 22 40 and 23 will be warp threads.

One essential characteristic of my improved fabric is the provision of a face formed largely of hard-finish and non-absorbent threads, thus providing a surface which is adapted to receive any 45 suitable dressing and which will somewhat closely simulate leather after said dressing is applied.

A further important characteristic of the invention is the provision of a relatively soft back, which particularly adapts the fabric to be used in 50 footwear where a soft inner surface is desired. This inner surface may be in white or in any desired light color.

It will be understood that the weaves herein shown are presented for purposes of illustration 55

only, and that the invention is not limited to a particular weave, so long as the described characteristics of the face and back of the fabric are retained.

5 Having thus described my invention and the advantages thereof, I do not wish to be limited to the details herein disclosed, otherwise than as set forth in the claims, but what I claim is:

1. A woven elastic fabric having the face there-
10 of formed in large part by fibrous hard-finish weft threads having a coating which renders them water-repellent and which are thereby adapted to receive a suitable dressing and simulate leather, and having the back thereof formed in large part by elastic warp threads having a soft and relatively thick covering, and said fabric having addi-
- 15

tional non-elastic and relatively small binder warp threads interposed between said elastic warp threads.

2. A woven elastic fabric having fibrous hard-finish weft threads floating on the face of the 5 fabric and having relatively soft weft threads floating on the back of the fabric, and having spaced covered rubber warp threads and interposed non-elastic warp threads interwoven with said face and back weft threads and retaining 10 said weft threads in the fabric, said hard-finish weft threads having a coating which renders them water-repellent and which adapts them to receive a dressing and simulate leather.

15

JOHN V. MOORE.
